RAILROAD TRACK STRUCTURE

Filed Sept. 19, 1928

Inventor:
William Dalton,
by *Alfred S. Babcock*,
His Attorney.

UNITED STATES PATENT OFFICE

WILLIAM DALTON, OF GLENVILLE, NEW YORK

RAILROAD-TRACK STRUCTURE

Application filed September 19, 1928. Serial No. 307,025.

The present invention relates to railroad track structures and especially to railroad track structures wherein the ties are formed of metal.

5 The object of my invention is to provide an improved construction and arrangement in a railway track structure of this type, and for a consideration of what I believe to be novel and my invention, attention is directed 10 to the following specification and the claims appended thereto.

In the drawing, Fig. 1 is a perspective view 15 of a track structure embodying my invention; Fig. 2 is a perspective view showing the invention as utilized at points where splice bars occur; Fig. 3 is a top plan view of a tie showing the type of insulating pad used at points where tie bars occur; Fig. 4 is a view 20 similar to Fig. 3 showing the type of insulating pad used where splice bars do not occur, and Fig. 5 is a sectional view through 25 a rail and fastener as shown in Fig. 1.

Referring to the drawing, 1 indicates a metal tie which in the present instance is 30 shown as comprising two lengths of bars fastened together at their ends by end plates 2 and at the points where the rails come by rail-supporting plates 3. The tie structure illustrated is of the general type of that disclosed in my Patent Number 1,657,241, dated January 24, 1928. Supporting plates 3 are tapered after the manner of standard tie plates so as to tip the rails inwardly at a slight angle and each is provided with two 35 sets of diagonally-arranged openings 4 and 5, the openings 4 being spaced for use when the rail-fasteners are to engage the rail flange directly and the openings 5 being spaced for use when the rail-fasteners are to engage a tie 40 bar. Preferably I utilize a rail-fastening means such as that disclosed in my Patent Number 1,657,242, dated January 24, 1928, the same comprising a U-shaped rail-clamping member 6 which is located in an opening 45 4 or 5 with its ends extending beneath the

supporting plate and over the rail flange, and a spring key 7 which fits in the opening behind the rail-clamping member 6 and serves to hold it in position.

I provide between the supporting plate 50 and the rail flange an insulating pad 8 formed from a yieldable material such as relatively soft rubber and beneath the U-shaped clamp I provide an insulating piece 55 9 formed of a suitable hard material such as hard rubber, fiber or the like, the insulating piece 9 and the clamp 6 being of such size that they serve to clamp the rail down tightly against the pad. Insulating piece 9 is provided with side flanges 10 which form a recess for the fastener whereby movement of the piece and fastener relatively to each other is prevented.

By the use of a yieldable pad beneath the rail in combination with a clamp which 65 clamps the rail down tightly on the pad, I obtain important new results in that the rail is held down firmly while at the same time the pad has resiliency sufficient to permit of the wave action which takes place in a rail 70 when a heavy load passes over it. Ordinarily such wave action is taken care of by leaving a clearance between the top of the rail flange and the fastener which means that the rail is not fastened down tight, a thing which 75 may in time result in unusual wear and other difficulties. The rail, so to speak, is yieldably fastened to the tie, the yielding action being sufficient to permit of the desired rail movement, but at the same time the rail being 80 held tight enough to prevent or at least greatly minimize wear. Also, the use of a yieldable pad has the further advantage that it serves to absorb vibration and deaden 85 noises, preventing to a considerable extent noises being transmitted to the coaches.

By clamping the rail down tight to the tie the further advantage is obtained that the use of anti-rail creeping means may be dispensed with, the clamping-down of the rail 90

in itself serving to prevent creeping of the rail.

I have found a pad made from rubber having a softness of the order of that used in the treads of automobile tires to be satisfactory and in using the term "soft rubber" I use it not as a definition of the degree of softness but to distinguish from hard, vulcanized rubber.

10 By providing the supporting plates 3 with two sets of openings 4 and 5, they are adapted to have fastened to them either the rail flange directly or the rail flange with a tie bar bolted thereto. For fastening the rail flange directly to the tie the inner openings 4 are utilized as is illustrated in Fig. 1. For fastening the rail flange with a tie bar as shown at 12 in Fig. 2, bolted thereto, the outer openings 5 are utilized. By this arrangement, a 15 standard supporting-plate can be used for all ties. It is desirable also, that the same fasteners 6 be used on both the inside and the outside of the rail flanges and to make this possible, I provide on the under surface of 20 plate 3 a groove 13 which is located in the vicinity of the openings 4 and 5 at the thicker side of the plate and is of a depth and width such that a fastener of the size to fit the inner edge of the rail flange will fit also the 25 outer side. In other words, the groove serves to make the plate adjacent the holes in the thicker portion of the plate the same thickness as the plate adjacent to the holes in the thinner portion of the plate. As is clear 30 from Fig. 5, the lower end of the U-shaped fastener 6 is located in the groove 13 and this is the case whether the fastener is in an opening 4 or an opening 5. As will be seen from Figs. 3 and 4, a slightly wider pad 8 (Fig. 3) 35 is used when the fasteners are to be located in openings 5 than is used when the fasteners are to be located in openings 4, (Fig. 4). Otherwise the pads 8 are the same. Also, the fastener 6 is of slightly different dimensions 40 when it is to engage a tie bar 12 than it is when it is to engage the rail flange directly. This means that in the utilization of my invention, the tie is in all cases a standard construction and also the other parts except that 45 50 where tie plates 12 occur a special pad and fastener is employed.

By locating openings 4 and openings 5 diagonally, I obtain a symmetrical fastening of the tie to the rail in each instance so that 55 in case the tie is lifted the strains are distributed to both sides of the tie.

What I claim as new and desire to secure by Letters Patent of the United States, is:—

1. In a railway track structure, the combination of a metal tie having a supporting plate which tapers in thickness, said plate being provided with openings at opposite edges to receive rail-fastening members, and a groove in the underside of the plate adjacent the opening at the thicker edge of the

plate of a depth such that the same kind of fasteners may be used in each opening.

2. In a railway track structure, the combination of a metal tie having a supporting plate provided with two sets of openings, the 70 openings of each set being diagonally arranged and the openings of one set being spaced apart farther than the openings of the other set for the purpose described.

In witness whereof, I have hereunto set 75 my hand this 15 day of September, 1928.

WILLIAM DALTON.
